J. RUDNICK

MEANS FOR FEEDING ADHESIVE MATERIAL TO BOX MAKING MACHINES

Filed Sept. 24, 1920

FIG. 1.

INVENTOR
Jacob Rudnick
BY
H. J. Bamford
ATTORNEY.

UNITED STATES PATENT OFFICE.

JACOB RUDNICK, OF NEW YORK, N. Y.

MEANS FOR FEEDING ADHESIVE MATERIAL TO BOX-MAKING MACHINES.

Application filed September 24, 1920. Serial No. 412,553.

To all whom it may concern:

Be it known that I, JACOB RUDNICK, a citizen of the United States, residing at the city of New York, county and State of New York, have invented a certain new and useful Means for Feeding Adhesive Material to Box-Making Machines, of which the following is a specification.

In the art of making paper boxes and cartons it is usual to employ a gang of machines each attended by two or more laborers for applying strips of material to the boxes during the process of making the same, such machines being known usually as "stripping machines." Each machine is equipped with an adhesive hopper or receptacle from which the material is fed as required by a roller dipping into the adhesive and over which roller the strip is moved by hand for taking up a film of the adhesive. It is common practice for one of the two attendants by a manual operation to replenish the supply of adhesive, which replenishment requires the attendant to carry a receptacle from a glue barrel to the stripper; such operations involving the dipping of the adhesive from the barrel, carrying it to the machine, and pouring it into the machine hopper or receptacle, in the course of which procedure a considerable waste of glue takes place. The deposit of the adhesive accidentally upon the floor leaves the latter in an unsanitary, and often a filthy, condition, and the time required for the attendant to replenish the supply amounts in the course of a year to a considerable item in the way of wages, for the reason that while one attendant is engaged in such task the other attendant remains idle for the period required to perform the labor, in addition to which the adhesive frequently becomes filled with foreign matter owing to the storage of such material in an open barrel exposed to dust and dirt.

According to the present invention, the foregoing objections are overcome, at least to a great extent, with the result that time and labor are economized, the floor remains in a sanitary, cleanly condition, and the adhesive is free from dust and dirt.

My invention is embodied in the form of a feed pipe positioned in an elevated relation to the adhesive hoppers of a gang of box making or stripping machines, said feed pipe being provided with a series of branch pipes leading to the adhesive hoppers and

each branch pipe having a gate or valve within easy reach of the attendant, so that it is only necessary to open the gate or valve for the required supply of adhesive to run from the pipe into the hopper.

The adhesive is stored in a tank, and between the tank and the feed pipe is a stand pipe, the latter being normally filled with the liquid or semi-liquid adhesive so as to establish a certain head or pressure by which the material is impelled to flow within the feed pipe, provision being made for blowing out said feed pipe in order to free it from material which might otherwise tend to obstruct or clog up said pipe.

Other features and advantages of the invention will appear from the following description taken in connection with the drawings, wherein—

Figure 1 is a plan view illustrating so much of a gang of stripping machines as is necessary to an understanding of my invention, and

Figure 2 is an elevation illustrating the means for feeding the adhesive material at will to either of a series of the receptacles of the gang of box making machines.

As shown in the drawings, the desired number of box making machines A are arranged in parallel order, sufficient space being left between the machines of the gang or series for the accommodation of the two operators required to perform the labor of "stripping" (applying strips to the boxes) during the process of making the same. The box making or stripping machines may be of the usual or any preferred construction, and, as shown, each machine is provided with a hopper or receptacle B for the adhesive material, said receptacle having a feed roller b mounted to dip into the adhesive material, and as a strip of paper, or its equivalent, is drawn over and into contact with said roller, the latter is rotated and a thin film of glue is applied to the strip of material, all of which operations are performed in a manner well understood by those skilled in the art.

Instead of replenishing the hoppers or receptacles B by manual labor as heretofore practiced, I provide means operable at will for controlling the feed of the adhesive material to the machines separately. In a preferred embodiment the feed means consists of a horizontal pipe or main C positioned in an elevated relation to the gang

of machines A, said feed pipe or main being out of the way of the operators stationed at the machines. The feed pipe or main is supported by any suitable means (not shown), and said pipe or main is provided with a desired number of branch pipes D, each having a valve or gate d. The branch pipes depend from the feed pipe or main toward and over the receptacles or hoppers B, and when the valve or gate d in each branch pipe is opened, the liquid material is free to flow by gravity from the pipe C through the branch pipes D directly into the hopper B.

15 Provision is made for storing a relatively large quantity of the adhesive material, it being preferred to use a feed tank E, supported in a raised position above the horizontal plane of the pipe C by a stand e, or equivalent supporting means. Said tank E is a closed receptacle of any suitable character, whereby dirt and dust can be kept out of the liquid material. The adhesive material has a tendency to settle within the tank, and in order to maintain such material at the proper constituency, I provide means for agitating the material as desired.

30 The agitating means is shown as a shaft F, the lower end of which is supported in a step bearing f affixed to the bottom of the tank, said shaft being provided with blades or wings f'. The agitator shaft F extends upwardly through the top of the tank, so that said agitator may be driven by a shaft G having a pulley g.

35 The adhesive material is of such consistency that it flows sluggishly within the feed pipe or main C, and it becomes necessary to provide some means for impelling the liquid material within the pipe. In the preferred embodiment of the invention I employ a stand pipe H intermediate the horizontal feed pipe C and the elevated tank E, said stand pipe being of such height and capacity that it contains normally a sufficient quantity of the liquid material to establish a head or pressure operating to impel the liquid material within the said pipe C. The 40 stand pipe is coupled at its lower end to the feed pipe or main C, whereas the other end of said stand pipe is coupled to the lower portion of tank E.

45 A strainer h is provided across the inlet to the stand pipe in order to exclude foreign matter from the stand pipe H and the feed pipe C. Said stand pipe is provided with a gate or valve h' which normally remains in an open condition for the flow of the 50 adhesive material by gravity from the tank

E into the stand pipe, but said valve or gate h' may be closed at any time when it becomes necessary to cut off the stand pipe H from communication with the tank E.

55 The adhesive material has a tendency to clog or obstruct the feed pipe or main, and at times it becomes necessary to clean out the feed pipe. To enable the cleaning out operation to be performed with ease and facility, I provide the feed pipe at one end with removable closure i, whereas the other end, i' of the feed pipe, is extended beyond the stand pipe H, as shown in Figure 2, said extension i' being readily accessible, and the extended end portion of the feed pipe being closed up by a removable plug j. It will be understood that the plugs i, j may be removed from the respective end portions of the horizontal feed pipe, and any suitable cleaning medium may be applied to 80 said feed pipe C for blowing out the matter which clogs or obstructs said pipe.

Having thus fully described the invention, what I claim as new and desire to secure by Letters Patent is—

85 1. An apparatus of the class described, embodying a plurality of box making machines each provided with a hopper and with means for supplying an adhesive to material adapted to be manipulated by an attendant, an adhesive feed tank in elevated relation to said box making machines, a feed pipe adjacent the hoppers of said machines, said feed pipe having means for controlling the distribution of adhesive material to the 90 hoppers of the individual machines, and a stand pipe connected to the tank and to the feed pipe for establishing the head or pressure required to feed the adhesive material to said feed pipe and said distributing 95 means.

100 2. In an apparatus of the class described, the combination with a gang of box machines, and a tank for adhesive material, of a feed pipe in elevated relation to said machines, the end portions of said feed pipe being accessible and provided with closures adapted to be removed for permitting the pipe to be cleaned, a stand pipe connected with the feed pipe intermediate the ends thereof and connected also with the tank for establishing the head or pressure required to impel the flow of material within said pipe, and means for distributing 105 material from the feed pipe to the individual machines at will.

110 In testimony whereof I have signed my name hereto this 23rd day of September, 1920.

JACOB RUDNICK.
